(57) CLAIM

The ornamental design for cored-out cutlery, as shown and described.

DESCRIPTION

FIG. 1 is a perspective view of a cored-out cutlery of the present invention;

FIG. 2 is a top plan view thereof;

FIG. 3 is a cross-sectional view taken through line 3—3 of FIG. 2;

FIG. 4 is a bottom plan view thereof; and,

FIG. 5 is a side elevational view thereof.

The broken lines shown in the drawings are for illustrative purposes only and form no part of the claimed design.
